UNITED STATES PATENT OFFICE.

GEORGE L. THEIGE, OF WESTBY, WISCONSIN.

DOOR-OPENER.

SPECIFICATION forming part of Letters Patent No. 749,339, dated January 12, 1904.

Application filed September 14, 1903. Serial No. 173,151. (No model.)

To all whom it may concern:

Be it known that I, GEORGE L. THEIGE, a citizen of the United States, residing at Westby, in the county of Vernon and State of Wisconsin, have invented certain new and useful Improvements in Door-Openers, of which the following is a specification.

This invention provides a mechanical device for simultaneously opening or closing a plurality of doors, shutters, or like closing means.

The device embodied in the invention is especially adapted for use in connection with tobacco-curing barns, which are, as is commonly known, provided with a number of doors upon all sides which when open permit a thorough ventilation of the barn and facilitate the drying of the tobacco which is disposed therein.

For a full description of the invention and the merits thereof and also to acquire a knowledge of the details of construction and the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of the door-opener device in applied position. Fig. 2 is a top plan view of the opener device disposed also in an operative position and showing its relative disposal when the doors are thrown open. Fig. 3 is an enlarged perspective view of the operating-bar carrying the arms. Fig. 4 is a transverse sectional view through the operating mechanism and the adjacent parts to which the same is attached. Fig. 5 is a detail view showing most clearly the exact form of the clamp members upon the U-shaped arms.

Corresponding and like parts are referred to in the following description and indicated in all the views of the drawings by the same reference characters.

The device is shown disposed upon the side wall 1 of a tobacco-barn, the side wall having a number of doors 2 hinged thereto at suitable intervals. The doors 2 may be of any type and are adapted to swing outwardly in a

manner readily seen. It will be understood that the doors may be provided in any number and that the operating-bar 3, by which the said doors are simultaneously thrown open or shut, may be provided with means for connecting the same to such doors. Each of the respective doors 2 is provided with brackets 4, which are suitably secured to the doors by substantial fastening means.

The operating means comprises a longitudinal bar 3, before mentioned, and arms 5, projected from the aforesaid bar and adjustably mounted for movement thereon. The bar 3 may be of any length, and the arms 5, being adapted for adjustment with reference to the bar 3, permit the use of the latter in connection with doors which may be disposed at intervals of different lengths and also admit of ready removal of the arms from certain doors should it be desired that the same be not operated along with the doors which remain connected to the bar. The arms 5 are of peculiar form, each comprising a body 5^a, of approximately U shape, having spaced clamp members 5^b laterally projected therefrom. The members 5^b embrace the operating-bar 3 upon opposite sides, and openings are disposed upon the ends of the members 5^b to receive a clamp element 7, by which the members 5^b are caused to firmly clamp the operating-bar. By loosening the clamp element 7 each arm 5 may be given a longitudinal movement upon the operating-bar 3 to properly adjust the same with reference to the door to which it will be attached. Obviously by entirely removing the clamp element 7 the arms 5 may likewise be removed from the operating-bar. Corresponding ends of the U-shaped bodies 5^a of the several arms 5 are received between the brackets 4, projected from the doors 2 and pivotally secured in such a position by means of a transverse pin or the like. By the provision of U-shaped parts 5^a upon the arms 5 the operating-bar 3 is rigidly maintained in position relative to the doors, and at the same time the exact form of these arms permits of throwing open of the doors, since the line of draft is in a lateral direction relative to the brackets 4. Handles 8 are provided at each end of the operating means, so that the doors

2 may be thrown open by an operator standing at either end of the operating-bar by a pull or push movement of the said bar.

In order that the doors 2 may be held open at different positions, a bracket 9, projected from the building or wall upon which the doors are disposed, is utilized, the said bracket being provided with spaced members disposed upon opposite sides of the operating-bar 3. 10 Openings in the spaced members of the bracket 9 receive a pin 10, which is also adapted to pass through a plurality of spaced openings 11 upon the operating-bar 3, so that the position of the bar 3 may be fixed at different points in its longitudinal movement. 15

Having thus described the invention, what is claimed as new is—

1. In combination with a plurality of doors, an operating-bar disposed adjacent thereto, 20 approximately U-shaped arms projected from the said operating-bar and having corresponding end portions secured to the door.

2. In a device of the class described, the combination with a plurality of doors, an operating-bar disposed adjacent the said doors, and U-shaped arms adjustably mounted upon the said operating-bar and pivotally connected to the said doors. 25

3. In a device of the class described, the combination with a plurality of hinged doors, an operating-bar disposed adjacent the said doors, arms provided with spaced members to embrace the operating-bar connected to the doors, means for clamping the spaced members of the arms about the operating-bar. 30

4. In a device of the class described, the combination with a plurality of hinged doors,

an operating-bar disposed adjacent the said doors, arms removably secured to the operating-bar and pivotally connected to the doors, 40 and means for co-operation with the operating-bar to fix the position of the same at different adjustments.

5. In a device of the class described, the combination with a plurality of doors, brackets projected from the doors, an operating-bar disposed adjacent the doors, arms secured to the operating-bar aforesaid, said arms comprising a U-shaped body and laterally-spaced members, the latter adapted to embrace the operating-bar upon opposite sides, clamp means disposed upon the lateral members of the arms aforesaid to cause clamp action of the said members upon the operating-bar. 45

6. In a device of the class described, the combination with a plurality of doors, brackets projected therefrom, an operating-bar disposed adjacent the doors, U-shaped arms adjustably mounted upon the operating-bar and pivotally secured to the bracket upon the doors, the operating-bar being provided with a plurality of openings therein, a fixed projection disposed adjacent the operating-bar, and a pin adapted to be passed through the said projection and any selected opening in 60 the operating-bar to thereby adjustably fix the position thereof. 65

In testimony whereof I affix my signature in presence of two witnesses.

GEORGE L. THEIGE.
